[57] CLAIM

The ornamental design for a vehicle panel instrument, as shown and described.

DESCRIPTION

FIG. 1 is front view of a vehicle panel instrument showing my new design;

FIG. 2 is a left side view thereof;

FIG. 3 is a bottom view thereof;

FIG. 4 is a right side view thereof;

FIG. 5 is a top view thereof;

FIG. 6 is a right front perspective view thereof; and,
FIG. 7 is a rear view thereof.

The dotted line showing of the support structure for an instrument is for illustrative purposes only and forms no part of the claimed design.
